US00D789372S

(12) **United States Design Patent** (10) **Patent No.:** **US D789,372 S**
(45) **Date of Patent:** **** Jun. 13, 2017**

(54) **SENSOR WAND**

(71) Applicant: **HipScience, LLC**, Orlando, FL (US)

(72) Inventor: **Marquette Trishaun**, Orlando, FL (US)

(73) Assignee: **HIPSCIENCE, LLC**, Orlando, FL (US)

(**) Term: **15 Years**

(21) Appl. No.: **29/564,966**

(22) Filed: **May 17, 2016**

(51) LOC (10) Cl. **14-02**

(52) U.S. Cl.

USPC **D14/433**

(58) **Field of Classification Search**

USPC D14/356, 432-434, 453, 454, 511, 203.8, D14/209.1, 238.1, 240, 125; 439/638, 439/928, 105, 502; 710/303, 304; 361/679.41, 679.55, 679.56; D13/110, D13/133, 146

CPC H01R 24/64; H01R 24/62; H01R 12/714; H01R 13/506; H01R 13/6658

(57) **CLAIM**

The ornamental design for a sensor wand, as shown and described.

DESCRIPTION

FIG. 1 is an upper front right perspective view of the novel sensor wand.

FIG. 2 is a lower front right perspective view of the sensor wand of FIG. 1.

FIG. 3 is an upper rear left perspective view of the novel sensor wand of FIG. 1.

FIG. 4 is a lower rear left perspective view of the novel sensor wand of FIG. 1.

FIG. 5 is a front side view of the sensor wand of FIG. 1.

FIG. 6 is a rear side view of the sensor wand of FIG. 1.

FIG. 7 is a right side view of the sensor wand of FIG. 1.

FIG. 8 is a left side view of the sensor wand of FIG. 1.

FIG. 9 is a top view of the sensor wand of FIG. 1; and,

FIG. 10 is a bottom view of the sensor wand of FIG. 1.
